MAURICE J. SCHLESS, OF NEW YORK, N. Y.

JEWEL SETTING

Application filed August 4, 1930. Serial No. 472,868.

This invention relates to a setting for jewels and other ornamental stones.

The primary object of the invention is to provide a setting which will greatly enhance the appearance of a jewel or other ornamental stone, when secured therein, by making the jewel or stone appear larger than it really is; and in the case of a jewel cut with a round face or what is known in the trade as a "brilliant" cut, the invention seeks to make the stone appear as a square stone or one of other more valuable shape.

The foregoing objects are attained by mounting a jewel in a plate formed and designed so as to present a substantially rectangular or other regular polygonal surface around the stone in such manner that it continues the reflection of the stone to straight side margins of a rectangle or other polygon.

20 The plate is so formed that the stone mounted therein appears to be secured by four or more straight-sided and bevelled securing elements or prongs in the body of the article of jewelry which it is to ornament.

25 These and other objects of the invention and the means for their attainment will be more apparent from the following detailed description, taken in connection with the accompanying drawings illustrating one embodiment by which the invention may be realized, and in which:—

Figure 1 is a view showing, in plan, the display face of a jewel mounted in the novel setting of this invention.

35 Figure 2 is a view, in plan, showing a plate for a setting constructed according to this invention.

Figure 3 is a view, in plan, of a jewel setting box for the plate.

40 Figure 4 is a view in elevation of the structure shown in Figure 1.

Figure 5 is a fragmentary sectional view along the line 5—5 of Figure 1 showing a jewel mounted in the setting.

45 Referring first to Figures 3 and 4, a substantially rectangular boxlike member 10 forms the base or support for the jewel setting of this invention. The sides of the box 10 are cut away, as at 11. In Figures 2, 4 and 5, there is shown a plate 12 also of sub-

stantially rectangular shape, superimposed upon the box 10, which plate is provided with cutaway portions 13 upon each of its four sides adapted to register with the cutout portions 11 of the box. The plate 12 is formed 55 with an opening 15, preferably centrally located, which is tapered to conform generally to the shape of the under surface of the jewel or other ornamental stone 16 to be mounted therein. The plate 12 is secured upon the box 60 by soldering the corners 17 thereof to the corners 9 of the box 10 or attaching them together in some other equally practical manner. The straight-sided corner portions 17 of the plate 12, defined by the cutouts 13, are 65 milled to form ledges consisting of the vertical surfaces 18 and the horizontal reflecting surfaces 19 disposed below the surface of the plate 12. The outer margins of ledges are bevelled, if desired, to form inclined reflect- 70 ing surfaces 20.

The jewel or other ornamental stone 16 is secured in the plate 12 in any convenient manner. As shown, the opening 15 is formed with a slightly crimped edge into which the stone 75 is sprung, as illustrated in Figure 5.

The cutaway portions 11 of the jewel box 10 coincide or register with the cutaway portions 13 of plate 12 so that the corners 17 of the plate 12 entirely cover the corre- 80 sponding corner portions 9 of the box 10 between the cutouts 11 and, as seen in plan view in Figure 1, only the bottom surfaces 14 of the cutouts 11 of the box 10 are visible. These, being much below the corners 17, give 85 the effect on the eye of the observer that the corners 17 are prongs engaging a jewel.

The flat surface of the plate 12, being made of any suitable metal for jewelry settings and being highly polished, reflects light which 90 merges with the reflection from the jewel and thereby the jewel appears of an increased area. Since the box is rectangular, the jewel appears of a rectangular shape. This gives the impression of a larger jewel cut to a more 95 valuable shape. The corners 17 of the plate produce the effect of prongs, which, by virtue of the cutouts 11, appear raised a substantial distance from the body of the article of jewel- 100 ry which the jewel is to ornament, as if for

the purpose of providing sufficient room for the anterior portion of the large stone which appears to be mounted therein. While in the embodiment illustrated there is shown a round jewel, it is to be understood that a square or other shaped stone may be used, the opening 15 being made to conform to whatever shape jewel is employed.

The box 10 is attached to the article of jewelry in any customary or desired manner.

It will thus be seen that there is provided a new and useful jewel setting which by its novel formation enhances the beauty of any jewel mounted therein and greatly increases the value thereof by causing the mounted stone to appear of a more valuable shape and size.

Various modifications will occur to those skilled in the art in the composition, configuration and disposition of the component elements going to make up the invention as a whole, as well as in the selection and combination of such component elements and no limitation is intended by the phraseology of the foregoing specification, or illustrations in the accompanying drawings, except as indicated in the appended claims.

What is claimed is:—

1. In a jewel setting, a substantially rectangular mounting plate formed with a jewel receiving aperture, means to secure a jewel therein, attaching means integral with the plate and comprising projecting corners having straight sides parallel to the sides of the plate and being cut away on the upper surfaces to form recessed reflecting surfaces lying in a plane parallel to the plane of the plate surface.

2. In combination a substantially rectangular plate formed with a jewel receiving aperture, jewel securing means, attaching means integral with the plate and comprising projecting corners having sides parallel to the sides of the plate, a supporting jewel setting box comprising four substantially rectangular walls with upper portions cut away to form a recessed surface on each side between the corners in a plane substantially parallel to the plane of the face of the plate.

50 In testimony whereof I affix my signature.

MAURICE J. SCHLESS.
